DRILL

Charles H. Gardner, Jr., Pleasant Grove, Calif.

Application January 15, 1940, Serial No. 314,002
In Canada January 17, 1939

7 Claims. (Cl. 77—32)

My invention relates to drills, particularly of the portable type, and has among its objects and advantages the provision of novel means for applying pressure on the drill for advancing the bit into the work being drilled, with the pressure applying means so devised as to relieve the operator of the manual effort necessary in connection with conventional portable drilling devices.

The present application is a continuation in part of my copending application, Serial No. 186,475, filed January 22, 1938, which has issued as Patent No. 2,196,208, dated Apr. 9, 1940.

In the accompanying drawing:

Figure 1 is an elevational view of a conventional portable drill showing my invention applied thereto;

Figure 2 is an enlarged sectional detail view of the pressure applying mechanism; and

Figure 3 is a sectional view of a control valve.

In the embodiment selected to illustrate my invention, I make use of a conventional drill of the portable type, which drill includes a body or housing 10 provided with a motor for driving the drill chuck 12. Such drills are well known in the art and need not be described in further detail.

Referring to Fig. 2, a cylinder 14 has one end threadedly connected at 16 with a plate 18 bolted at 20 to the body 10. Inside the cylinder 14 I slidably mount a piston 22 which includes an actuating rod 24 having a metallic disc 26 fixedly secured to its inner end. Shaft 24 is preferably provided with a shank 28 disposed in a bore 30 in the disc 26, and a dished element 32 is fixedly secured to the shank 28 by a bolt 34 so that the disc 26 will be held in place on the shank. Element 32 includes a flange 36 fitting snugly against the inner wall of the cylinder 14 to establish a seal. Element 32 may be somewhat flexible so that the flange 36 will be pressed against the inner wall of the cylinder 14 as the piston 22 is moved downwardly.

Cylinder 14 includes a transverse wall 38 having a bore 40 for slidably receiving the rod 24, and the rod extends through a packing gland 42, with the outer end of the rod provided with a head 44 adapted to be positioned against an abutment for applying drilling pressure to the drill or bit connected with the chuck 12. With the head 44 positioned against an abutment, introduction of liquid under pressure into the chamber 46 in the cylinder 14 will urge the piston 22 upwardly which causes the head 44 to press against the abutment for exerting downward pressure on the drill bit.

Upon the plate 18 I mount a reservoir cylinder

48 and threadedly connect this cylinder with the plate at 50. Inside the cylinder 48 I slidably mount a piston 52 of the same general type as the piston 22, and between the piston 52 and the closure plug 54 I mount a compression spring 56 which tends to move the piston 52 downwardly. The chamber 58 in the cylinder 48 is filled with a suitable liquid, which liquid may be pumped into the chamber 46 for applying drilling pressure.

Body 10 includes a hand grip 60 through the medium of which the drill is manipulated for position placement purposes as well as carried from place to place. Upon the grip 60 I mount a cylinder 62 provided with a slideable pump plunger 64 manipulated through the medium of a handle 66 fixedly secured to the outer end of the plunger 64. Between the upper end of the cylinder 62 and the arm 68 of the handle 66 I mount a compression spring 70 which normally moves the plunger 64 to its outer extreme position.

Cylinder 62 includes a valve body 74 having a bore 76 provided with a valve seat 78 and a valve 80 arranged to permit liquid to flow from the chamber 82 of the cylinder 62, with the valve 80 arranged to close to prevent the entrance of liquid thereto. Valve body 74 is provided with a tube 84 connected at 86 with the cylinder 14, which tube establishes communication between the chambers 46 and 82. Valve body 74 is also provided with a valve seat 88 and a valve 90 arranged to admit liquid to the chamber 82 but operating to prevent outward flow of the liquid. A tube 92 connects with the valve body 74 and the cylinder 48, as at 94. Thus the tube 92 establishes communication between the chambers 58 and 82.

Interposed in the tubes 84 and 92 is a valve body 96 having a rotatable plug 98 provided with bores 100 and 102. Plug 98 may be rotated through the medium of a wing 104. With the plug 98 positioned according to Fig. 3, bore 100 aligns with the two sections of the tube 84 and the bore 102 aligns with the two sections of the tube 92.

In operation, the chambers 46 and 58 are supplied with a suitable liquid and such liquid may be taken from the chamber 58 and delivered to the chamber 46 through manipulation of the plunger 64 for exerting drilling pressure on the piston 22. Spring 56 exerts a constant pressure on the piston 52, which pressure is transmitted to the liquid in the chamber 58. Thus the tube 92 is supplied with liquid at all times which permits the drill to be operated at different angles. Valves 80 and 90 constitute checks so that the liquid may be effectively transferred from the

chamber 58 to the chamber 46, while liquid pumped into the chamber 46 is held therein by reason of the valve 80. Valve plug 98 is positioned according to Fig. 3 during operation of the plunger 64.

Rotation of the plug 98 through ninety degrees from the positions of Figs. 2 and 3 brings the bores 100 and 102 to the dotted line positions of Fig. 3 so that the sections of the tubes 84 and 92 between the valve body 96 and the chambers 46 and 58, respectively, are placed in direct communication which permits liquid to flow from the chamber 46 back to the chamber 58. The tension of spring 56 is of sufficient strength to insure proper delivery of the liquid to the tube 92, but the spring tension is such that a slight downward pressure on the head 44 will transfer liquid in the chamber 46 back to the chamber 58. Wing 104 is so arranged as to extend longitudinally of the tubes 84 and 92 when the valve plug 98 is adjusted according to Fig. 3, so that the wing acts as an indicator to determine the position of the valve plug.

Having thus described certain embodiments of my invention in detail, it is, of course, understood that I do not desire to limit the scope thereof to the exact details set forth except insofar as those details may be defined in the appended claims.

I claim:

1. In a drill of the type described, a drill pressure means, a pump controlled fluid circuit for operating said drill pressure means to apply pressure to the drill, and a pressure reservoir for delivering fluid to said circuit.
2. In a drill of the type described, a drill pressure means, a fluid circuit for operating the drill pressure means to apply pressure to the drill, pump means in said fluid circuit for placing the fluid acting on said drill pressure means under drilling pressure, and a pressure reservoir for delivering fluid to said fluid circuit.
3. In a drill of the type described, a drill pressure means, a pump controlled fluid circuit for operating said drill pressure means to apply pressure to the drill, a pressure reservoir for delivering fluid to said circuit, and a valve means for by-passing fluid acting on said drill pressure means to said reservoir.
4. In a drill of the type described, a drill pressure means, a fluid circuit for operating the drill

pressure means to apply pressure to the drill, pump means in said fluid circuit for placing the fluid acting on said drill pressure means under drilling pressure, a pressure reservoir for delivering fluid to said fluid circuit, and a valve means for by-passing fluid acting on said drill pressure means to said reservoir.

5. In a drill of the type described, a first cylinder having a drill pressure means movably related thereto and arranged for engagement with a relatively fixed abutment to advance the drill, a liquid circuit for operating the drill pressure means to apply pressure to the drill, a second cylinder for a reservoir body of liquid connected into said liquid circuit, means for placing the liquid in said second cylinder under pressure for delivering the liquid to said liquid circuit, and pump means in said liquid circuit for placing the liquid acting on said drill pressure means under drilling pressure.

6. In a drill of the type described, a first cylinder having a piston slidable therein, with the piston provided with a pressure element adapted to be placed in abutting engagement with a relatively fixed abutment to advance the drill, a second cylinder containing a supply of liquid, a pump, a conduit between said second cylinder and said pump, a conduit between said first cylinder and said pump, valves in said conduits for controlling the flow of liquid from said second cylinder to said first cylinder, and a resiliently urged piston in said second cylinder for delivering liquid to the pump to be pumped to said first cylinder.

7. In a drill of the type described, a first cylinder having a piston slidable therein, with the piston provided with a pressure element adapted to be placed in abutting engagement with a relatively fixed abutment to advance the drill, a second cylinder containing a supply of liquid, a pump, a conduit between said second cylinder and said pump, a conduit between said first cylinder and said pump, valves in said conduits for controlling the flow of liquid from said second cylinder to said first cylinder, a resiliently urged piston in said second cylinder for delivering liquid to the pump to be pumped to said first cylinder, and valve means interposed in said conduits for establishing direct communication between said first and second cylinders.

CHARLES H. GARDNER, JR.
